TELESCOPE MOUNTING FOR GUNS

John H. Redfield, Denver, Colo.

Application February 8, 1938, Serial No. 189,307

2 Claims. (Cl. 33—50)

(Cl. 33—50)

This invention relates to a means for mounting a telescopic gun sight upon a gun and has for its principal object the provision of a mounting which can be quickly and easily applied to the gun; which will enable the telescope to be quickly removed and rapidly and accurately replaced; which will support the telescope with absolute rigidity so as not to be affected by the recoil of the gun; and which will have an accurate windage control.

Other objects and advantages reside in the detail construction of the invention, which is designed for simplicity, economy, and efficiency. These will become more apparent from the following description.

In the following detailed description of the invention reference is had to the accompanying drawing which forms a part hereof. Like numerals refer to like parts in all views of the drawing and throughout the description.

In the drawing:

Fig. 1 is a side elevation of a typical rifle with the mounting and telescope in place thereon.

Fig. 2 is a side elevation of the mounting with
25 the position of the telescope indicated thereon
in broken line.

Fig. 3 is a bottom view, looking upwardly, of the base member of the mounting.

Fig. 4 is a top view of the forward extremity of the base member.

Fig. 5 is a cross section taken on the line 5-5, Fig. 2.

Fig. 7 is a side elevation of the forward tele-

Fig. 7 is a side elevation of the forward telescope clamp.

40 Fig. 9 is a cross section through the base mem-

In the drawing a typical rifle is designated in the entirety by the numeral 10, the receiver thereof by the numeral 11, and a typical tele-

45 The invention employs a base member 13 designed to be secured upon the top of the receiver 11 by means of suitable attachment screws for which screw openings 14 are provided in the base member. One side edge of the base member 13 is cut back as indicated at 15 and the remainder of the base member at this point is beveled as indicated at 16 to allow for the entry of the 50

55 The rear portion of the base member is formed indicated at 16 to allow free passage for the ejected shells from the receiver.

with a concave boss 17 which fits into a coacting depression in the receiver 11 to maintain the rear portion of the base member in alignment. The bottom forward portion of the base member is formed with a concavity 18 which fits snugly over the forward portion of the receiver 11. 5

A transverse, elongated opening 19 opens through the upper face of the forward portion of the base member. This opening communicates within the base member with a round opening 20 formed in the bottom of the base member. The round opening joins the elongated opening to form two inclined convex shoulders 21. The inclined shoulders 21 do not extend completely to the bottom of the base member but terminate slightly above the bottom to form a narrow circular guide edge about the opening 20.

The rear portion of the base member is drilled and threaded entirely through its width, as shown at 22, to receive a pair of oppositely facing headed screws 23. These screws are formed with a convex undersurface on their heads so as to provide a relatively sharp wedge-like edge around the under face of the head. The screws are so positioned that their heads project above the upper surface of the base member 13.

The telescope is held by means of a front clamping sleeve 24 and a rear clamping sleeve 25 clamped about the telescope by means of suitable clamping screws 29. Both clamping sleeves are formed with flat plane bottoms which rest accurately upon the flat plane upper surface of the base member 13.

The forward sleeve 24 is provided with a circular, conical tenon 26, the sides of which are flattened, as shown at 27, so that the bottom outline of the tenon is identical to the shape of the elongated opening 19. The tenon is placed in the opening by holding the telescope transversely of the elongated opening 19. The tenon is placed in the opening by holding the telescope transversely of the rifle barrel 10, as indicated in Fig. 4 with the tenon in alignment with the barrel. The telescope is then swung to a position of alignment with the barrel which turns the tenon into position beneath the beveled shoulders, as shown in Fig. 3. As the tenon is turned beneath the shoulders, it contacts therewith to draw the member 24 snugly down upon the base 13 so that it cannot vibrate or move.

The rear clamping sleeve 25 is formed with semi-circular wedge grooves 27 at each of its sides and when in place on the base, these grooves receive the wedge edges of the screws 23 so that

both lateral and vertical movement of the member 25 is prevented.

It can be readily seen that the windage of the telescope can be adjusted by simply loosening one of the screws 23 and tightening the other. It can also be seen that by loosening one of these screws, the telescope can be swung to the position of Fig. 2 and lifted from the base member. When in place the telescope will be rigidly held 10 against movement in any direction.

While a specific form of the improvement has been described and illustrated herein, it is desired to be understood that the same may be varied, within the scope of the appended claims, 15 without departing from the spirit of the invention.

Having thus described the invention, what is claimed and desired secured by Letters Patent is:

20 1. A telescope mounting for guns comprising: an elongated base member affixed to the receiver of a gun; a front telescope clamp pivotally

mounted on the forward extremity of said base member to swing in a horizontal arc; a rear telescope clamp having a flat bottom resting on the rear portion of said base member; and a screw threaded into each side of said base member, said screws engaging opposite sides of the said rear telescope clamp, the heads of said screws being recessed so as to provide a sharpened peripheral edge axially thereof, said clamp being arcuately recessed for the reception of said edge. 10

2. In a telescope mounting for guns of the type having a telescope engaging member and a base member supporting said engaging member, means for fixedly securing said engaging member on said base member comprising: a headed 15 screw threaded into said base member from each side thereof, the heads of said screws being recessed to provide a sharpened, circular peripheral edge directed axially thereof, said engaging member being arcuately recessed for the reception of 20 said edge.

JOHN H. REDFIELD.
